3
TEST 1

Hypothermic activities of compounds (I) were tested using mice, to which 150 milligrams of the test compound per kilogram of body weight was intra-peritoneally administered to give the result shown in Table I, where the activity is expressed in terms of the drop of body temperature in degree(s) centigrade.

TABLE I.—DROP OF BODY TEMPERATURE (° C.)

Test Compound	Time after administration (minutes)						
	15	30	60	90	120	150	180
A	2.45	2.60	2.10	1.35	1.00	0.70	0.35
B	2.00	2.30	2.30	2.30	1.70	1.55	1.35
C	2.25	2.50	2.00	1.50	1.35	1.10	1.10
D	1.40	1.80	1.90	1.95	1.85	1.25	1.25
E	2.40	2.90	2.15	1.65	1.10	0.45	0.20
F	2.85	3.15	1.30	0.95	0.85	0.55	0.45
Control	1.55	1.65	0.95	0.45	0.25	0.10	0

TEST II

Anti-inflammatory activities were tested according to the method described in Proc. Soc. Exp. Biol. Med., vol. 3, page 544 (1962), against edema caused by the injection of carrageenin in rats. The results are shown in Table II in which the activities are expressed in terms of inhibition percentages.

TABLE II.—INHIBITION PERCENTAGE IN CARRAGEENIN EDEMA

Test Compound	Time after administration (hours)				
	1	2	3	4	5
D	37	74	70	67	65
Control	50	66	51	46	47

TEST III

Median lethal doses (LD_{50}) of the compounds (I) in mice when administered intraperitoneally are shown in Table III, from which it is noted that the compounds of the present invention show very low toxicity:

TABLE III

Compound:	LD_{50} (mg./kg.)
B	1,550
C	1,640
G	1,630
Control compound	720

As shown in the above tests, the compounds of Formula I have very low toxicity and exhibit remarkable hypothermic effect.

The compounds of the present invention are used as a pyretolytic agent or as an anti-inflammatory agent for mammals, and also to suppress pain caused by inflammation.

When the group R_2 of the compound (I) is one derived from a polybasic acid, irrespective of whether it is inorganic or organic, by the removal of an OH therefrom, the compound (I) constitutes a partial ester and can form a salt with a metal (such as sodium, potassium, magnesium) or an amine (such as diethylamine, triethylamine, ethylenediamine, diethanolamine or ammonium), and in so far as the salts are pharmaceutically acceptable, they are also used for the same purpose as the corresponding partial ester and on the same molar basis.

In human beings, the dose of present compound (I) is usually 500 to 2500 milligrams per day and the compounds (I) are generally administered in the form of capsule, tablet, syrup, injection, ointment, etc.

The following examples show presently preferred embodiments of this invention but are not to be construed as restrictive. It is to be understood that the following examples are solely for the purpose of illustration and not for limitation of this invention, and that variations may be resorted to without departing from the spirit of the invention. In the example, parts by weight bear the same relation to parts by volume as do grams to milliliters.

4
EXAMPLE 1

4.7 parts by weight of p-isobutylbenzoylmethyl iodide (M.P. 60° C.), 2.2 parts by weight of nicotinic acid and 4.5 parts by weight of triethylamine are dissolved in 30 parts by volume of acetone. The mixture is left standing at room temperature for five hours. After the acetone has distilled off, 50 parts by volume of ether and 20 parts by volume of water are added to the residue, and the mixture is shaken. The ether layer is extracted with 30 parts by volume of 10% hydrochloric acid, and the acid solution is alkalinized with sodium carbonate and is extracted with ether. The ethereal extract is washed with water and dehydrated over anhydrous sodium sulfate, and the ether is distilled off to leave 1.2 parts by weight of p-isobutylbenzoylmethyl nicotinate as pale yellow prisms melting at 93° C., the hydrochloride of which is soluble in water.

Analysis.—Calculated for $C_{18}H_{18}O_3N$ (percent): C, 72.70; H, 6.44; N, 4.70. Found (percent): C, 72.29; H 6.38; N, 4.64.

The starting material, p-isobutylbenzoylmethyl iodide, is prepared, for example, by reacting p-isobutylbenzoylmethyl chloride with sodium iodide in acetone.

EXAMPLE 2

To a mixture of 6.3 parts by weight of trisilver phosphate and 3.6 parts by weight of 85% phosphoric acid, there are added 50 parts by volume of acetonitrile and 6 parts by weight of p-isobutylbenzoylmethyl iodide. After the whole mixture is refluxed for four hours under mild heating with agitation, the resultant precipitates are filtered off and from the filtrate the acetonitrile is distilled off. Water is added to the residue, followed by the addition of activated carbon to adsorb the product thereon. The carbon is filtered off, washed with water and eluted with an aqueous sodium hydroxide solution. The eluate is concentrated under reduced pressure, and acetone is added to the concentrate to precipitate sodium salt of p-isobutylbenzoylmethyl phosphate.

EXAMPLE 3

A mixture of 4.9 parts by weight of p-cyclohexylbenzoylmethyl iodide, 15 parts by weight of sodium acetate and 150 parts by volume of acetone is boiled for one hour, and the solvent is distilled off. Ether and water are added to the residue, and the mixture is agitated. The ether layer is separated from the aqueous layer, and is concentrated. After the addition of about the equi-volume of petroleum ether to the concentrate the mixture is left standing to give 1.8 part by weight of p-cyclohexylbenzoylmethyl acetate as colorless prisms, melting at 77° to 78° C.

The starting material, p-cyclohexylbenzoylmethyl iodide is prepared by, for example, reacting p-cyclohexylbenzoylmethyl chloride with sodium iodide in acetone.

EXAMPLE 4

49 parts by weight of p-cyclohexylbenzoylmethyl iodide is added to the slurry obtained by the reaction of 60 parts by weight of trisilver phosphate and 50 parts by weight of 85% phosphoric acid in 100 parts by volume of acetonitrile in the presence of 5 parts by weight of diatomaceous earth, and the mixture is boiled while being agitated for 3.5 hours. After cooling, 200 parts by volume of water is added to the reaction mixture, and the resultant mixture is adjusted to pH 7.5 by the addition of a 20% aqueous sodium hydroxide solution to precipitate silver iodide, which is then filtered off. The filtrate is concentrated under reduced pressure to remove acetonitrile. 120 parts by weight of activated carbon is added to the residue. After being adjusted to pH 2 with hydrochloric acid, the mixture is filtered to collect the activated carbon, which is then washed with water until the washing shows pH 4. The washed carbon is suspended in methanol, and the suspension is adjusted

to pH 8 by the addition of a 20% aqueous sodium hydroxide solution and is extracted with 2000 parts by volume of methanol. The methanol extract is concentrated under reduced pressure. Acetone is added to the concentrate to precipitate sodium p-cyclohexylbenzoylmethylphosphate.

The NMR (nuclear-magnetic resonance) of the product in D_2O shows doublet at 4.8τ , which reveals that methylene is attached to

In the same manner as in the preceding examples, the alkyl benzoylmethyl derivatives listed in the following Table IV, are produced.

- 15
- 6
3. A compound according to claim 1, the compound being p-isobutylbenzoylmethyl phosphate.
  4. A compound according to claim 1, the compound being p-cyclohexylbenzoylmethyl phosphate.
  5. A compound according to claim 1, the compound being p-sec-butylbenzoylmethyl phosphate.
  6. A compound according to claim 1, the compound being p-tert-butylbenzoylmethyl phosphate.
  7. A compound according to claim 1, the compound being p-n-butylbenzoylmethyl phosphate.
  8. A compound according to claim 1, the compound being p-n-octylbenzoylmethyl phosphate.
  9. A compound according to claim 1, the compound being p-cyclopentylmethylbenzoylmethyl phosphate.

TABLE IV

Example	R_1	R_2	X	Boiling point (2 mm.)	NMR(τ) Hg, °C.
5	$CH_3 \cdot CH_2 \cdot CH \cdot$ CH ₃	$-COCH_3$	H	¹ 4.82(S) 135-145

¹ S=Singled.

² d=Doublet.

What is claimed is:

1. A compound of the formula

wherein R_1 is a hydrocarbon residue having from 4 to 8 carbon atoms and is straight or branched chain alkyl or cycloalkyl or cycloalkylalkyl, and X is either hydrogen or chlorine.

2. A compound according to claim 1, wherein the compound is in the form of a pharmaceutically acceptable salt.

10. A compound according to claim 1, the compound being p-cyclohexyl-m-chloro-benzoylmethyl phosphate.
